CLAIM

The ornamental design for a binocular reflector telescope, as shown and described.

DESCRIPTION

FIG. 1 is a side elevation of a binocular reflector telescope showing my new design;

FIG. 2 is an end elevation as seen from the right of FIG. 1;

FIG. 3 is an end elevation as seen from the left of FIG. 1;

FIG. 4 is a perspective view as seen from the left of FIG. 1;

FIG. 5 is a perspective view as seen from the right of FIG. 1;

FIG. 6 is a fragmentary cross-section taken on line 6—6 of FIG. 5; and

FIG. 7 is a fragmentary elevation taken in the direction of line 7—7 of FIG. 6.

FIG. 1.

FIG. 2.

FIG. 3.

FIG. 4.

FIG. 5.

FIG. 6.

FIG. 7.
